CLAIM

The ornamental design for a drill inclinometer attachment, as shown and described.

DESCRIPTION

FIG. 1 is a diagrammatic perspective view of the drill inclinometer attachment;

FIG. 2 is a left side elevational view thereof, the right side view being a mirror image of the left side view;

FIG. 3 is a top plan view of the drill inclinometer attachment;

FIG. 4 is a bottom plan view thereof;

FIG. 5 is a front elevational view thereof; and,

FIG. 6 is a rear elevational view thereof.
